UNITED STATES PATENT OFFICE.

JOSEF STREDA, OF TRUTNOV, CZECHOSLOVAKIA.

DEVICE FOR RAISING PETROLEUM AND THE LIKE.

Application filed November 13, 1922. Serial No. 600,733.

To all whom it may concern:

Be it known that I, JOSEF STREDA, a citizen of the Republic of Czechoslovakia, residing at Trutnov, Czechoslovakia, have invented 5 certain Improvements in Devices for Raising Petroleum and the like, of which the following is a specification.

In raising liquid out of petroleum wells and the like by means of the ordinary 10 bailers, which consist of a tube having in its lower end a non-return valve, it frequently happens that the bailers, when arriving at the well head, are almost exhausted of liquid. This is due to the fact that the 15 liquid is saturated with gas which expands on reaching altitudes of lower atmospheric pressure and which, in leaving the bailer, carries the liquid with it.

The object of the present invention is to 20 remedy this defect, and the invention consists in providing the bailer with an additional valve seat in the upper end of the tube and suspending the bailer on a valve body which cooperates with this seat so as 25 to keep the bailer closed against internal pressure while it is being raised, both valves being open during the filling of the bailer which is then either supported on the bottom of the well or partly suspended in the liquid.

30 As difficulties may be experienced in the opening of the lower valve for emptying the bailer, if the pressure in the latter is allowed to rise excessively, the upper valve body is formed with vents through which the gas 35 can escape without entraining the liquid, and means are provided for regulating the vent area according to requirements.

Fig. 1 of the drawings represents a vertical section of the head of the apparatus in 40 its simplest form of construction, and

Fig. 2, a cross-section of the same on the line X—X of Fig. 1.

Fig. 3 is a vertical section of a different construction, and

Fig. 4, an elevation of this construction.

Fig. 5 is a vertical section showing a further development of the invention,

Fig. 6, a vertical section of one of the elements employed therein, and

Fig. 7, a cross-section on the line Y—Y of Fig. 5.

The apparatus is composed of a tube A within the upper end of which a valve seat 8 is formed by means of a sleeve 6 secured

55 within the tube through the medium of rivets 7. The round head 2 of a valve body

B fits the seat 8 and also serves as a support for the tube, the body B being fitted at the upper end with an eyelet 5 whereby the whole apparatus can be suspended on a rope 60 or the like. Thus the apparatus can be lowered through the borehole into an oil-well for raising oil from the latter. As the apparatus descends, the oil and the gas 65 enter the tube A from below and drive the air out of it, as the tube is then partly suspended in the liquid. When the apparatus is raised, however, its whole weight will be taken up by the valve head 2 which then prevents the air from re-entering the tube 70 and the liquid from leaving it.

To relieve overpressure, the valve head 2 is formed with vents 4 which are drilled obliquely from the upper part of the head towards a large center hole 3 which is drilled 75 from the bottom. The vents 4 are screw-threaded so that they can be stopped by screws for regulating the vent area in accordance with the prevailing gas pressure.

For constructional reasons the eyelet 5 may be screwed onto the valve stem 1, for which purpose screw-holes 9 are made in the socket 6 and in the tube wall for the temporary reception of clamp screws 10, the latter being employed for gripping the valve 80 stem while the eyelet is being applied.

For oil wells with considerable gas pressure, the apparatus is preferably constructed as shown in Figs. 3 and 4. In this case there is a sleeve 11 secured by rivets 7 to the upper end of the tube A, the valve seat 8' being formed in a separate sleeve 6' which is screwed into the sleeve 11. A screw 35 is fitted in a drill hole made at the junction of the two elements. This screw, which is itself retained in position by means of a locking pin 36, prevents the two elements from relative rotary displacement. Above the valve seat there is in the sleeve 6' a downwardly projecting lip 38 which forms 90 behind it a ring-shaped space 39. There are also vents 37 made in the sleeve 6' for the escape of gas.

The valve head 2' has an internal valve seat 17 for a ball 18, the seat being formed by a hollow plug 14 which is screwed into a wide center bore 3' in the head. The plug has a head 15 which is formed with circumferential notches 16 for cooperation with a spanner. A cross-pin 14' locks the plug 14 105 to the valve head. From the bore 3' a narrower bore 13 is run right through the valve 110

stem 1'. The bore 13 guides a bar 19 which bears with its enlarged and hollowed lower end against the ball 18 so as to hold the latter against the seat 17. A spring 21, which fits the reduced upper end 20 of the bar exerts pressure on the latter and on the ball, the upper end of the spring being supported by a screw 20 through the medium of a variable number of plugs 22 which take the thrust. 10 The screw 20 can be adjusted for regulating the pressure of the spring on the ball valve.

The eyelet 25 for the reception of the hoisting rope, is made in a vertical, tapered plate 12 which is screwed onto the valve stem 1' by means of a boss B' and locked in position by means of a cross-pin 23. Feet 24 are formed on the plate 12 for abutment against the sleeve 6' when the apparatus is not suspended on the valve head. The boss B' has an aperture to admit the screw 20. A locknut 26 for the screw, bears against the boss, and is itself locked by means of a screw 27 which fits in the plate 12 and which engages with apertures 28 made in the circumference of the nut. 25

Vents 4' are made in the valve head 2' so as to set the space 3' above the ball valve 18 into communication with the space above the valve head 2'. There are also vertical bores 29 made in the head 2' around the bore 3'. These bores communicate through ducts 33 with the vents 4' but are normally closed by balls 32 which are supported by springs 31. Hollow screw plugs 30 are fitted in the lower ends of the bores 29 so as to support the springs 31. Transverse ducts 34 in the stem 1' also establish communication between the bore 13 and the outside space. 30

40 The modus operandi is as follows:—

When the apparatus is lowered into the well, as previously described, the oil and gas enter the tube A where they are retained by the closing of the valves when the apparatus, 45 suspended on the valve head 2', is raised. At the expansion of the enclosed gases, the spring 21, which is adjusted for a certain pressure, allows the ball valve 18 to open. The gas then escapes through the vents 4' which are directed towards the space 39. 50

Oil particles contained in the gas, will be retained in the space and fed back into the tube instead of being expelled at the top of the same and lost. The same occurs with oil 55 particles carried away by the gas through the ducts 34, the latter being directed towards the sides of the sleeve 6'. When the apparatus has been raised out of the well, it is supported on an oil receiver for the discharge of the contents. The 60 springs 31 are adjusted so as to hold the ball valves 32 normally against their seats. The discharge of the contents begins, however, before the valve head 2' has properly left its seat, and if any vacuum should be

created in the tube, the valves 32 open so as to admit air. Thus a rapid and uniform discharge of the contents will take place.

In Figs. 5 to 7, an additional mechanism is shown which enables the apparatus according to Figs. 3, and 4 to be used for drawing liquid from various levels, for instance from the upper or lower portion of an oil layer or from a water layer situated beneath it. For this purpose the plug 14 70 is extended downwards beyond the head 15 in the form of a rod 40 which is surrounded by a coil spring 51. A washer 50, which is supported on the rod by a nut 48, forms a support for the lower end of the spring, and 80 the upper end of the spring bears against a plate 46 which admits the rod through an aperture 47. The plate 46 is fitted in the lower end of a sleeve 44 which is secured to the valve seat sleeve 6' and which is 85 formed with lateral apertures 45. A bore 41 in the rod 40 communicates with the valve space 3' and also, through lateral apertures 42 with the tube space. The nut 48 is adjusted for regulating the spring and is 90

locked in adjusted position by means of a cross-pin 49 which passes through apertures 43 in the rod. In this case the weight of the apparatus is carried by the spring 51 which, while the apparatus descends into the well, 95 prevents the valve 2' from reaching the seat 8'. Thus the apparatus can pass easily through the liquid which is free to enter at the bottom of the tube and leave at the top of the same, and the tube will at each moment be filled with liquid from the particular layer through which it passes. When the apparatus arrives in the position from which liquid is to be drawn, the descent is stopped, and as the upward movement begins, the spring 51 is unable to cope with the additional weight. The valve 2' will then be placed against its seat, and the contents of the tube will follow it to the surface. By this arrangement it is possible to draw 100 liquid from any particular layer without mixing it with that of other layers through which it has to pass. 105

By means of this apparatus the productivity of an oil-well can be considerably 110 increased.

I claim:—

1. A bailer of the character described for raising liquid out of petroleum wells, comprising a valve body having an enlarged 115 valve head, a bailer tube having in its upper part a valve seat whereby it can be suspended on said valve head, and means for suspending the apparatus through the medium of the valve body so as to prevent the liquid 120 from being expelled by the expanding gases when the apparatus is raised. 125

2. A bailer of the character described for raising liquid out of petroleum wells, comprising a valve body having an enlarged 130

- valve head, a bailer tube having in its upper part a valve seat whereby it can be suspended on said valve head, and means for suspending the apparatus through the medium of the valve body so as to prevent the liquid from being expelled by the expanding gases when the apparatus is raised, the valve head being provided with vents through which gas can escape so as to relieve overpressure.
3. A bailer of the character described for raising liquid out of petroleum wells, comprising a valve body having an enlarged valve head, a bailer tube having in its upper part a valve seat whereby it can be suspended on said valve head, means for suspending the apparatus through the medium of the valve body so as to prevent the liquid from being expelled by the expanding gases when the apparatus is raised, the valve head being provided with vents through which the expanding gases contained in the oil can escape, and means for trapping and retaining oil particles carried away by such escaping gas.
5. A bailer of the character described for raising liquid out of petroleum wells, comprising a valve body having an enlarged valve head, a bailer tube fitted at its upper end with a valve seat whereby it can be supported on said valve head, means for connecting the valve body to a hoisting element, a spring supporting the tube on the valve body, and means for adjusting the spring so that it prevents the valve head from reaching its seat while the apparatus descends and allows it to close against the seat, so as to retain the liquid in the tube, under the strain of the hoisting element in lifting the apparatus, substantially as and for the purpose set forth.
6. A bailer of the character described for raising liquid out of petroleum wells, comprising a valve body having an enlarged valve head, a bailer tube having in its upper part a valve seat whereby it can be suspended on said valve head, means for suspending the apparatus through the medium of the valve body so as to prevent the liquid from being expelled by the expanding gases when the apparatus is raised, the valve head being provided with vents for admitting air into the tube while the valve bears against the seat, and spring-pressed valves normally
- closing such vents and adapted to open when the pressure in the tube falls below that of the atmosphere, substantially as and for the purpose set forth.
